UNITED STATES PATENT OFFICE.

MARY MILLER, OF THERESA, WISCONSIN.

SEED-SPROUTER.

1,267,330.

Specification of Letters Patent.

Patented May 21, 1918.

Application filed November 10, 1917. Serial No. 201,310.

To all whom it may concern:

Be it known that I, MARY MILLER, a citizen of the United States, residing at Theresa, in the county of Dodge and State of Wisconsin, have invented new and useful Improvements in Seed-Sprouters, of which the following is a specification.

This invention is an improved apparatus for sprouting seeds or grains, especially oats, for use to feed chickens and other fowls, the object of the invention being to provide an improved apparatus of this kind which is extremely simple in construction and which utilizes the heat radiated from a tank of hot water in maintaining the temperature at the required degree to facilitate the sprouting of the oats and avoids the use of a lamp or other like heating device and hence obviates the danger of setting fire to the apparatus or the building in which the same may be used.

The invention consists in the construction, combination and arrangement of devices hereinafter described and claimed.

25 In the accompanying drawings:

Figure 1 is a perspective view of my improved oats sprouter, with the door open.

Fig. 2 is a detailed vertical sectional view of the same.

30 In the embodiment of my invention I provide a casing or structure 1, which is upright and of oblong rectangular form, comprising a bottom 2, top 3, sides 4, back 5, and a door 6 which forms a front. The 35 back, front and sides are each made of ship-lap lumber 7 lathed on the inner side as at 8 and the laths covered on the inner side as at 9 with waterproof japonized paper or other suitable insulating material; laths 10 40 are applied over the insulating paper so that dead air spaces are formed. The top and bottom are each composed of two thicknesses of lumber 12 and hence the casing is adapted to retain heat for a considerable length

45 of time. Strips of lathing 14 are secured vertically on the inner sides of the side walls 4 and in spaced relation to each other and provided with horizontally arranged cross bars 15 which serve to support and permit the ready removal of a series of sprouting trays 16 which are arranged in superposed relation and of which six are preferably employed as shown. The inner sides of the back and the front door are

also provided with vertically arranged 55 lathing strips 17 and hence when the trays are in place and the doors are closed spaces are formed between the trays and spaces are also formed between the sides and ends of the trays and the opposing back, front 60 and side walls of the casing so that heat radiated from a tank 19 and containing hot water and placed in the bottom of the casing, below the lowermost sprouting tray, is permitted to reach and is substantially 65 evenly distributed between all of the sprouting trays. An opening 20 is provided in the top of the casing and suitable fastening devices 21 are provided to secure the door when closed.

70 The tank is preferably made of galvanized iron and is provided with a filling nipple 22. The bottom, sides and ends are covered with heavy perforated corrugated paper and an outer covering of canvas as at 75 23 and the top of the tank is covered with a single thickness of pasteboard 24.

In the use of my improved apparatus the oats are first soaked in warm water for twenty-four hours, then drained, supplied 80 again with warm water and stirred and kept therein for a few minutes, then again drained and the trays placed in the casing and each tray covered with a heavy cloth or piece of grain bag or the like and which 85 should be pressed firmly down. The tank is kept supplied with hot water, which should be renewed two or three times per day according to weather conditions. In practice a new tray of swelled oats should 90 be supplied to the apparatus at each feeding from the bottom, and the oats to be used at a feeding should be taken from the uppermost tray, all the trays being raised as a new tray is supplied at the bottom so that 95 each tray remains in the apparatus six days, which is the period required for thoroughly sprouting the oats.

While I have herein shown and described a preferred form of my invention, I would 100 have it understood that changes may be made in the form, proportion and construction of the several parts, without departing from the spirit of my invention and within the scope of the appended claim.

Having thus described my invention, I claim:

A grain sprouter comprising a casing,

vertically arranged spacing strips secured to the side and end walls of the casing, vertically spaced horizontal supporting strips secured to the spacing strips of the end walls, a hot water tank arranged in the bottom of the casing, trays removably arranged in vertical spaced relation on the horizontal

supporting strips and spaced from the side and end walls of the casing by the vertical strips, whereby heated air may freely circulate about the trays. ¹⁰

In testimony whereof I affix my signature.

MRS. MARY MILLER.
